UNITED STATES PATENT OFFICE

CHARLES HULTGREN, OF CHICAGO, ILLINOIS, ASSIGNOR TO S. KARPEN & BROS., OF CHICAGO, ILLINOIS, A CORPORATION OF WEST VIRGINIA

DAY BED

Application filed December 4, 1922. Serial No. 604,876.

This invention relates particularly to a type of furniture known as the day bed, but the construction is equally adapted for a davenport or sofa bed. The principal objects of the invention are: to provide a construction of this kind which is solidly supported in open and in closed positions; to assist the overturning movement of the seat with a spring; to raise the seat from its closed position in overturning it so that the construction when folded will be close to the floor; to provide improved pivoting and overturning supports at the ends of the seat; and in general, to provide the construction herein shown and described.

In the accompanying drawings, Fig. 1 is a view with one end of the day bed removed, illustrating the preferred embodiment of my invention, the broken outline showing the seat in raised position; Fig. 2 is a similar view showing the seat overturned and the bed bottom extended; Fig. 3 is a sectional view showing one end of the day bed. Figure 4 is a broken view showing the position of the operating parts when the seat is closed; and Figure 5 is a view with parts broken away showing the seat in partially raised position.

In a day bed the two ends are unconnected above the seat at either side while a davenport or sofa bed has a back along one side either stationary or raisable, so that the construction of the present invention is applicable to either type of furniture. It is desirable that the seat shall not be too high above the floor, that sufficient space is provided beneath the seat for accommodating the folding bed construction, mattress and bed clothes, and that sufficient space is afforded for upholstering the seat to make it soft and comfortable.

In carrying out the present invention, a pair of ends 1 are provided which may be made entirely of wood or may be frames covered or partially covered with upholstery, and beneath the two ends an upholstered seat 2 is mounted for overturning movement. A metal frame 3 is provided at each end and it is preferably seated within the end 1 by recessing the inner side of the end or by making

it with projections 4 at the edges of the inner side of sufficient depth to receive the metal frame 3. This frame 3 may be permanently attached to the ends 1 but it is preferably made removable by means of bolts 5 projecting inwardly from the frame end 1 through the metal frame 3 and held in place by wing nuts 6. At one side of the sofa bed usually called the back, is a fixed base board 7 permanently attached to the metal frames 3 and 55 corresponding in appearance to a front board 8 which is attached to the opposite side of the seat 2. Extending below the end frames 3 is a connecting strip 9 to assist in bracing them against movement apart. The front 60 side covered by the front board 8 is usually left unbraced so that a supporting member is needed to strengthen the frames. If the front board 8 is broken or divided lengthwise, the lower portion of it is attached at the 65 ends to the frames 3, to brace them, in accordance with well known practice.

The upholstery of the seat 2 is mounted upon a frame 10 of wood or metal so that the upholstered part can be built up of springs 75 and fabric making a soft edge all around. Mounted on the underside of the seat is a bed bottom comprising a plurality of pivotally connected sections 11, 12 and 13. The bed bottom is connected to the seat frame by 80 means of a fixed bracket 14 at each end of which the intermediate section 12 is pivoted and by means of a slotted guide 15 in which a headed pin 16 attached to one of the sections 11 is slidable. When these sections are foldable under the seat they are held in place by a pivoted lock 17 attached to the front board 8, and when the sections are unfolded, as shown in Fig. 2, the outer sections 13 are supported by means of legs 18 pivotally connected at the outer side of each section 13, and connected by means of a link 19 with the pivot of brace 14, and each leg 18 being strengthened against lateral movement by a brace 20.

In mounting the seat for its overturning movement, a pair of links 21 and 22 are connected to a pivot 21^a at each end of the seat frame 10 adjacent the center thereof. One link 21 has a fixed pivotal connection 21^b 100

with the frame 3 or an extension 23 thereof, and the other link 22 is pivotally connected at its other end 22^a to a lever 24, the lever being pivoted at 24^a to the top cross piece of the frame 3 and having a bent downwardly turned extremity 25 to which one end of a spring 26 is connected, the other end of the spring being connected to a fixed portion of the frame 3. Also connecting the seat 1 and the frame 3 is a link 27 pivotally connected to the frame 3 at 24^a adjacent the center thereof and at 27^a to the seat frame 10 between the pivotal connection of the links 21 and 22 therewith and the inner edge of the seat.

The links 21 and 22 normally rest in either open or closed portion of the seat on the upper cross piece of the frame 3, as shown by both of Figs. 1 and 2. The links are preferably of double thickness, as shown in Fig. 3, made by folding a piece on a central fold line thus giving added strength and rigidity. In operation the links 21 and 22 together with the lever 24 act as swinging bars for raising the axis of the seat and thereby actually shifting the fulcrum upon which the seat is overturned. The result is that the seat normally lies as close to the floor as possible, but it will swing freely without touching the floor in overturning it, as the fulcrum is shifted upwardly before the seat is inverted.

For limiting the movement of the seat in either direction, a projecting bracket 28 is attached to the seat frame which is adapted to engage a corresponding stop 29 attached to the end frame 3 in one position and to engage another stop 30, also attached to the frame 3, in the overturning position, as shown in Fig. 2. This also takes some of the weight from the seat pivots, reducing the wear upon them.

In assembling this structure, the metal end frames 3, the links, and all the connecting parts are attached to the seat frame and the rear board 7 and the under supports 9 are attached to the end frames entirely separate from the sofa bed ends 1. The structure thus described is entirely capable of complete action in overturning the seat without the attachment of the ends 1, and the ends can therefore be attached by simply inserting the bolts 5 through the corresponding holes in metal end frames 3 and tightening the bolts in place. This can easily be done when the seat is in an intermediate position, as shown by the broken outline in Fig. 2 whereupon the construction will be ready for use.

If desired, the bed portion may simply cover the under side of the seat, making a narrow single bed without any folding sections. It will also be observed that for the overturning action, only the links 21 and 27 are absolutely necessary, the links 22, levers 24, and springs 26 producing a more smooth and balanced action. Practically the same

result is accomplished when the spring is attached to an extension of the link 21 below its pivot point.

In operation the structure is normally assumed as a day bed with the upholstered seat uppermost, as in Fig. 1. In this position the appearance of both sides is substantially the same, and as the links 21 and 22 are resting on the upper edge of the frame 3 there is no tendency whatever for the seat to tip on either side. In order to overturn the seat and extend the bed the lower edge of the front board 8 is grasped and raised upwardly which will cause a toggle action of the links 24 and 22 raising the fulcrum of the seat, this action being assisted by the spring 26. When raised to the uppermost position, as shown in the broken outline in Fig. 2, the seat is easily overturned, the rear or lower edge swinging above and entirely clear of the floor until the underside of the seat is uppermost, with the links 21 and 22 again lowered and resting upon the upper cross piece of the end frame 3, as clearly shown in Fig. 2. In changing from one position to the other, the guide link 27 is turned from the right hand side of its pivot (as shown in Fig. 1) to the opposite side thereof when it assumes the inverted position. When the seat has been inverted, the lock 17 is turned to release the bed bottom sections from their connection therewith and the section 13 is folded outwardly. This causes the central section 12 to swing upon its axis raising the section 11 in the guide plate 15 and rotating the supporting legs 18 downwardly until the sections 11, 12 and 13 reach an alined position, as shown in Fig. 2. The structure is then capable of use as a bed, the mattress and bed clothes unfolding in the ordinary way with the bed sections.

When the structure is folded the reverse action takes place, the sections being first folded in the underside of the seat and the seat being overturned by the fulcrum raising toggle action of the links 21 and 22 until the seat assumes the day bed position.

For shipping purposes the ends 1 can be easily detached from the seat and packed or crated with it thereby occupying very little more space than the seat itself, thus commanding the completed article of furniture from the manufacturers standpoint.

I claim:

1. In an article of furniture of the class described, an overturning seat, a frame for the seat, and means including a pair of arms connecting the frame and seat at each end, and a lever connected to the frame and to the seat end of one of the arms for first raising and then swinging the seat in overturning it.
2. In an article of furniture of the class described, a seat invertible about an axis, and means for raising and swinging the axis in the action of overturning the seat, said means including pivoting arms connected at the axis,

- one of which has a fixed pivot at the other end and a lever connected to the other arm at its free end.
3. In an article of furniture of the class described, a seat having a fulcrum about which it is overturnable, and means for simultaneously swinging the fulcrum upwardly and forwardly in overturning the seat, said means including two arms pivoted at the fulcrum of the seat, one arm having a fixed pivot at the other end and the other arm having a swinging connection at its other end.
4. In a bed of the class described, a frame, an overturnable seat, means for mounting the seat for bodily raising and swinging movement when it is overturned, said means including a pair of pivoted arms connected to the seat and frame at each end thereof, a lever pivoted at one end to one of the arms, and a resilient member connected to the lever tending to swing the seat while it is being raised by the arms.
5. In a bed of the class described an invertible seat, toggle links connected to the seat for raising it, and a spring actuated lever connected to one only of the links to assist in swinging the seat as it is raised.
6. In a bed of the class described, a seat invertible about a horizontal axis, a pair of links connected to the same axis at each end, one of the links having a fixed pivotal support at the other end, and a lever having a pivoted connection with the other end of the other link to assist in swinging the seat upwardly and forwardly where it may be overturned.
7. In a bed of the class described, an invertible seat having a shiftable fulcrum, means including a spring impelled lever for shifting the fulcrum about which the seat is invertible, and a link having a fixed pivotal connection at one end and pivotally connected to the seat at the other end for limiting the direction of overturning of the seat.
8. In a day bed, an invertible seat, means including a pair of links for raising the seat fulcrum in overturning it, end frames each having a top cross bar engaged by the links in the limiting positions of the seat, and a separate link at each end of the seat pivotally connected to the said cross rail and to the seat for limiting the overturning movement of the seat and for additionally supporting the seat in its positions of rest.
9. In a bed, the combination with an overturning seat, of supporting end frames each having a top cross bar, links for raising the axis of the seat in overturning it, the links being supported by the cross bar in the two limiting positions of the seat, and co-operation projections at the ends of the frame and seat for additionally supporting the seat in both of its positions of rest.
10. In a day bed, a pair of bed ends each
- recessed on the inner side, a seat invertible about a horizontal axis between the ends, a supporting frame adapted to be seated in the recess of each bed end, a pair of links pivotally connected intermediate the sides at each end of the seat, a lever pivoted to the frame and connected to one of the links, a spring connected to the other end of the lever and partially seated in the recess, a link connecting the seat and the frame for limiting the overturning movement of the seat, and co-operating stops on the frame and seat for limiting the inverting of the seat in opposite directions.
